PIE PAN CRADLE

John C. Boyd and Antonia D. Boyd, both of 21654
Cherryland Court, Hayward, Calif. 94541

Filed July 1, 1974, Ser. No. 484,900

Term of patent 14 years

Int. Cl. D7—06

U.S. Cl. D7—130

FIG. 1

FIG. 2

FIG. 3

FIG. 4

FIG. 5

FIG. 1 is a perspective view of the pie pan cradle;
FIG. 2 is a top plan view thereof;

FIG. 3 is a bottom plan view thereof;

FIG. 4 is a side elevational view of FIG. 2, the opposite side elevational view being a mirror image thereof; and

FIG. 5 is a right end elevational view of FIG. 2, the opposite end elevational view being a mirror image thereof.

We claim:

The ornamental design for a pie pan cradle, as shown and described.
